DISPLAY BOX

Walter J. Tiskey, Montville, Conn., assignor to
Robertson Paper Box Company, Inc., Mont-
ville, Conn., a corporation of Connecticut

Application July 24, 1937, Serial No. 155,358

2 Claims. (Cl. 206—44)

This invention relates to a combined packaging and display box, the especial object being to provide such a combined box by which a number of articles may be boxed for shipment and held for sale, and articles therefrom mounted for display in front of a display card as desired. The box preferably is folded from a single blank but may be made otherwise.

For a full understanding of the invention, a detailed description of a display box embodying all the features of the invention in a preferred form will now be given in connection with the accompanying drawings illustrating such box, and the features forming the invention then particularly pointed out in the claims.

In the drawings:

Figure 1 is a perspective view of the box in display position, illustrating the box as designed for display of three brushes, one being shown in position in dotted lines;

Figure 2 is a perspective view of Figure 1 looking from the rear of the display card and with the compartment cover raised;

Figure 3 is a vertical longitudinal section of the box in display position as shown in Figure 2, the section being taken on the line 3 of Figure 4;

Figure 4 is a vertical cross section of the box in the same position, on the line 4 of Figure 3;

Figure 5 is a perspective view of the box closed, with the display card slightly raised to show the construction;

Figure 6 is a cross section of the box closed;

Figure 7 is a perspective view of the compartment partition;

Figure 8 is a detail of one of the display card holding tabs; and

Figure 9 is a plan of the preferred form of blank for folding to form the box.

The display box shown is designed for use with paint brushes and is illustrated as for containing and display of brushes of three different sizes or types, and will be so described.

Referring to the drawings, the box is formed of a bottom panel 10, side panels 11, 12, end panels 13, 14, and top panel 15, the panel 15 preferably having therein a swinging cover 16 closing the compartment for holding articles, as shown. The display card 17 is formed on a panel including a narrow panel portion 18 overlying the top panel 15 and glued thereto and on which the display card swings, and the display card has wings 19, 20 on opposite sides by which it is supported in inclined position on the box and is held firmly in such position by tabs 1 on the wings 19, 20 entering slits 2 in the top of the box at

its side edges. The panels 11, 12 are preferably provided with flaps 3, which fold over the bottom panel 10 and the end panels 13, 14 likewise have flaps 4 folding over the inside of the side panels 11, thus holding the box together when set up. 5 The display card panel 17 is shown as perforated and partially divided on the line 5 so that the end of the panel forms a flap 6 which folds over the inner side of the display card and strengthens it. 10

The top panel 15 and the overlying panel portion 18 and end panels 14, 15 are cut out as shown at 7 in the brush display box shown, so as to provide notches for mounting and holding the brushes as shown in Figure 1, the box illustrated 15 being adapted for holding brushes of three different sizes or types. The compartment at the rear of the box is closed by the cover 16 and the compartment preferably is divided into three sections by the folded longitudinal partition 21, 20 the front central wall of the partition blank having a cutout 8 to permit the mounting of the central brush in the holding notches 7.

A preferred form of blank for making the box, with the display card and its supporting wings 25 integral with the box, is shown in Figure 9, the lines of folding perforations in the blank for setting up the box with the display card in display position, as shown in Figures 1 and 2, or closed upon the top of the box, as shown in Figures 5 30 and 6, and for the swinging cover 16, being shown in dotted lines.

The blanks may be shipped flat and readily folded for setting up the box for packing and display. 35

If desired, however, the box may be made from one blank and the display card with its wings from a separate blank and mounted on the side edges of the box by its wings 18 and tabs 1 in the same way as when integral with the box. 40

It will be understood, also, that the box may be designed for articles other than brushes, and that the shape of the box and of the article holding recesses will be varied according to the articles for which the box is designed. 45

What I claim is:

1. A blank for a combined packaging and display box having box forming bottom, top, side and end panels, a swinging cover formed in the top panel, and a display card panel having side wings 50 for supporting the display panel in inclined position on the top of the box, the top panel and the front end panel having cutouts forming holding means for supporting articles in display position in front of the display card. 55

2. A combined packaging and display box having a compartment for holding a number of articles, said box having top and front panels, means for supporting selected articles in display position comprising notched portions formed jointly in said top and front panels, a cover in

hinged relation to said compartment, and a display card in hinged relation to said top panel and having supporting wings, said display card and supporting wings being foldable into positions for display and flat on said box cover.

WALTER J. TISKEY.
